UNITED STATES PATENT OFFICE.

HENRY G. VOIGHT, OF NEW BRITAIN, CONNECTICUT, ASSIGNOR TO RUSSELL & ERWIN MANUFACTURING COMPANY, OF NEW BRITAIN, CONNECTICUT, A CORPORATION OF CONNECTICUT.

LOCK.

973,728.

Specification of Letters Patent. Patented Oct. 25, 1910.

Application filed June 24, 1910. Serial No. 568,623.

To all whom it may concern:

Be it known that I, HENRY G. VOIGHT, a citizen of the United States, residing at New Britain, county of Hartford, State of Connecticut, have invented certain new and useful Improvements in Locks, of which the following is a full, clear, and exact description.

My invention relates to improvements in so-called corridor door locks, such as are particularly adapted for use in hotels.

In locks of this character it is common practice to provide mechanism which may be operated by a plurality of keys, such as a guest key, a master key for the use of the chambermaid on a single floor, a grand-master key for the use of the housekeeper and adapted to operate the locks on all floors, and a so-called emergency or proprietor's key by which access may be gained to all rooms under all circumstances and by which the lock may be so set that it cannot be operated by any but the emergency key. It is also common practice to provide such locks with mechanism such as the thumb-turn operable from the inner side, by which the latch bolt may be dead-locked against any key but the emergency key.

My invention contemplates improvements in locks of this particular construction whereby while the lock may be operated under ordinary conditions by all of the keys, it may be dead-locked against operation by the master and grand-master keys when locked by the guest key or the emergency key.

A further object of the invention is to provide the lock with mechanism operable from the inner side, such as a thumb-turn, by which the latch bolt may be dead-locked from the inside against operation by the master and grand-master keys, but may be operated from the outside by a duplicate guest key held by one of two occupants of a room and also by the emergency key.

Finally, my invention contemplates mechanism by which the latch bolt may be dead-locked by the emergency key against operation from the outside by the duplicate guest keys as well as the master and grand-master keys, but in which the latch bolt may nevertheless be operated from the inside by the thumb-turn.

In the particular embodiment of my invention herein disclosed, the same includes

so-called cylinder lock mechanism for operation of the latch bolt, but it is to be understood that my invention is not confined to this particular style of lock mechanism.

With the above objects in view, my invention consists in the construction and arrangement of parts, a preferred embodiment of which is illustrated in the accompanying drawings, in which—

Figure 1 is a side elevation of the lock with the cap or cover removed and looking toward the inner side of the door. Fig. 2 is a sectional view on the line 2—2 Fig. 1, looking to the left, with the cap plate and cylinder lock mechanism in place. Fig. 3 is a view similar to Fig. 1, showing the dead-locking mechanism in one of its dead-locking positions. Fig. 4 is a fragmentary view similar to Fig. 3, showing the dead-locking mechanism in another of its dead-locking positions. Fig. 5 comprises a side elevation and end view respectively of the dead-locking slide detached. Fig. 6 comprises a side elevation and plan view of one of the latch operating levers. Fig. 7 comprises opposite side elevations and an end view respectively of a tumbler for the dead-locking slide. Fig. 8 comprises a side elevation and end view respectively of the guard or emergency tumbler of the dead-locking slide. Fig. 9 comprises a side elevation and edge view of an intermediate lever co-operating with the latch operating lever. Fig. 10 comprises edge views of the key controlled cam arm for actuating the dead locking slide and co-operating with the guard tumbler respectively. Figs. 11, 12, 13 and 14 are views of the master, grand-master, guest and emergency keys respectively.

In the embodiment of my invention herein selected for illustration, 1 indicates the lock case having a face plate 2 and a cap plate 3 of the usual construction.

4 is a spring-actuated latch bolt mounted in suitable guide-ways within the lock case and having a stem 5 upon which is mounted a spring 6, by which the latch bolt is normally projected in the usual manner.

7 is a roll-back which co-operates with a spring slide 8 having a projection 9 engaging the cross head 10 on the stem of the latch bolt by which said latch bolt may be retracted by operation of said roll-back 7. It is to be understood, however, that in the con-

struction here shown only the knob on the inner side of the door is capable of operating the roll-back 7, the knob on the outer side being idle or stationary.

5 Above the latch bolt 4 a dead-locking slide 12 is mounted on suitable guide-ways 13 in the lock case, upon which slide a latch operating lever 14 is pivoted at 15, said lever having a stud 16 which normally lies in the 10 path of a projection 17 on the latch bolt stem. The opposite end of said latch bolt operating lever 14 is arranged to engage one end of a lever 18 pivoted at 19 also upon the dead-locking slide 12. The opposite end 15 20 of said intermediate lever 18 is arranged to lie normally in the path of a cam arm 21, Fig. 2, secured to the inner end of the cylinder plug 22 of a cylinder lock mechanism 23, in the usual manner, whereby when said 20 cam 21 is rotated by a suitable key, the latch bolt 4 may be retracted through the intermediate lever 18 and the latch operating lever 14.

With the mechanism in the position shown 25 in Fig. 1, the latch bolt may be retracted through the cam 21 by means of any of the keys of the series above referred to. The master key in Fig. 11 and the grand-master key (Fig. 12), however, are only of sufficient 30 length to extend through the key plug of the cylinder lock and operate only the cam 21 thereof. In order to dead-lock the latch bolt against operation by the master and grand-master keys, the dead-locking slide 35 12 may be moved from the position shown in Fig. 1 to that shown in Figs. 3 and 4, whereby the intermediate lever 18 and latch bolt operating lever 14 are moved out of 40 range of the rotation of the cam arm 21 of the cylinder lock mechanism.

The dead-locking slide is provided with a V-shaped tumbler 24 having an arm 25 provided with a gate 26 coöperating with a racking stump 27, by which said slide is 45 held either in its normal or dead-locking position, as shown in Figs. 1 and 3 respectively. This dead-locking operation may be performed in three different ways, viz., by the guest key or the emergency key from the 50 outer side or by a thumb-turn on the inner side of the lock. In case such dead-locking is effected by the guest key or thumb-turn, the dead-locking mechanism may be returned to normal position either by the 55 guest key, thumb-turn or emergency key. When the dead-locking slide is operated by the emergency key, however, it may only be returned to the normal position by the emergency key from the outside or by the thumb- 60 turn from the inside.

To effect dead-locking by the duplicate guest key *g* or the emergency key *e*, each of said keys, as shown in Figs. 13 and 14 respectively, are of greater overall length than 65 the master or grand-master keys, and at the

rear of the lock case and in alinement with the cam arms 21 of the cylinder lock mechanism 23 are the cam arms 28 and 29 rotatably mounted between the lock case and a bearing plate *x* (Fig. 2) and held against 70 accidental movement by the spring-pressed arms 28' and 29' respectively. Each of said cam arms 28 and 29 is provided with a key-receiving slot 30, Fig. 1, arranged in alinement with the key-hole slot of the cylinder lock 75 plug 22. The emergency key *e*, Fig. 14, while of greater overall length than the master and grand-master keys, is of less overall length than the guest key *g*, and is adapted when inserted in the cylinder lock 80 plug to extend beyond the cylinder plug only so far as to engage the key-receiving slot 30 of the rotary cam arm 29 nearest the cylinder lock mechanism, and hence rotates only the rotary cam arm 29 in addition to 85 the cylinder plug cam 21. The cam arm 29 is arranged in the same plane with the dead-locking slide 12, whereby it may engage the actuating notch 31 in said slide, to move the latter into or out of dead-locking position. 90 Furthermore, the tumbler 24 is provided with an arm 32 which is likewise engaged by the rotary cam arm 29 whereby said tumbler may be released from its racking stump 27 by said cam arm. Upon movement of the 95 dead-locking slide to the position shown in Fig. 3 by the cam arm 29, the intermediate latch operating lever 18 is moved out of range of the cylinder lock cam 21, as a result of which the latch bolt cannot be operated either by the short master or grand-master keys.

In a similar manner, the dead-locking slide may be moved to dead-locking position by means of the guest key, as follows: The 105 guest key is of sufficient overall length to extend not only into the key-receiving slot 30 of the cam arm 29, but also into the corresponding slot of the cam arm 28 to the rear of the first, whereby both of said cam 110 arms, as well as the cylinder lock cam 21, will be rotated by the operation of the guest key, and thus the dead-locking slide may be moved to and from operative position by the rotation of the cam arm 29. The purpose of 115 the cam arm 28, operable only by the guest key, is to prevent return of the dead-locking slide to normal inoperative position by means of the guest key when said slide is moved to operative position by the emergency key. To this end there is pivoted on the case at 33 beneath the dead-locking slide a guard tumbler 34 shown detached in Fig. 8, having a spring 35, by which the free end of said tumbler is normally lifted and held 120 in engagement with a stop 36, Figs. 3 and 4, in the lock case. The free end of said guard tumbler is also slotted at 37 to receive a lug 38 on the rear end of the dead-locking slide 125 when said tumbler is in its elevated position. 130

When the dead-locking slide is in its rear-most or normal inoperative position, Fig. 1, the lug 38 thereof lies to the rear of and outside of the slot 37, so that said guard tumbler may be rocked regardless of said lug. The rotary cam arm 28 lies in the same plane as the guard tumbler 34, and hence as said cam arm is rotated, together with the rotary cam arm 29, by the guest key; the 5 tumbler will be rocked downwardly against its spring so that as the dead-locking slide 12 moves forward to operative position, the lug 38 on said slide, instead of taking within the slot 37 of the guard tumbler, will ride 10 over the upper edge of said tumbler, as indicated in Fig. 3, thus permitting the rotary cam arm 28 to make a complete rotation and to return to its normal position, in which the key may be withdrawn from the cylinder lock. When, however, the dead-locking 15 slide is operated by means of the emergency key, the rotary cam arm 28 is not rotated, and hence as the dead-locking slide moves forward to operative position, the guard 20 tumbler 34 remains in its elevated or normal position, in which position the lug 38 of the locking slide passes within the slot 37 of said tumbler. Consequently, if it is now attempted to return the locking slide to normal 25 position by means of the guest key, the rotary cam arm 28, operated by said key, will come into engagement with the upper edge of the guard tumbler, thus rigidly held in its elevated position, whereby complete 30 rotation of the cam arm 28 and consequently also of the cam arm 29 by the guest key will be prevented. Hence, when said locking slide is moved to dead-locking position by the emergency key, it cannot be returned to 35 normal position by the guest key.

In order that the latch bolt may be deadlocked against operation by the master and grand-master keys from the inside, a thumb-turn 35' is provided on the inner side of the lock having a spindle which engages the hub 35 of roll-back arms 36, which overlie the lower arm 25 of the tumbler 24 and are adapted to operate the same, and thereby 40 actuate the dead-locking slide to which said tumbler is pivoted to and from operative position. To this end, the lower arm 25 of the tumbler 24 is provided with a laterally projecting ledge 37, Fig. 7, which terminates in a depression 38, having the actuating 45 surfaces 39 and 40 adapted to be engaged by the thumb-turn roll-back arms 36, whereby said tumbler may be released from the racking stump 37 and the dead-locking slide moved to or from operative position by 50 said roll-back arms.

In order that the dead-locking slide may be returned from operative to normal position by means of one of the duplicate guest keys after it has been so moved to dead-locking position by means of the thumb- 55

turn roll-back, it is necessary that the guard tumbler 34 be moved to and held in depressed position during such movement of the dead-locking slide to operative position by said roll-back, so that the cam arm 28 70 rotated by the guest key may rotate free of the guard tumbler. To this end the guard tumbler is provided with a lateral projection 41 arranged in the path of rotation of the thumb-turn roll-back arms 36, whereby 75 as said arms rotate, the guard tumbler will be drawn down until during the forward movement of the dead-locking slide, the lug 38 will pass over the upper edge of said tumbler, thus holding said tumbler in a position 80 to permit free operation of the rotary cam arm 28 as before described when it is desired to return the dead-locking mechanism to inoperative or normal position by means of the guest key. In order to prevent all possibility of jamming of the roll-back arms 36 and the guard tumbler projection 41 during the depression of said guard tumbler by said arms, said projection 41 is carried at the outer end of a swinging arm 42 pivoted at 85 43 on the free end of said guard tumbler, said swinging arm being provided with a spring 44 which yieldingly holds the projection 41 in proper position relative to the path of movement of the roll-back arms 36. 90 It will be seen, therefore, that the dead-locking device may be moved by the guest key, emergency key and thumb-turn to operative position so that the latch operating levers 14 and 18 are carried entirely out of 95 range of the cylinder plug cam 21; that when the latch is so dead-locked by the thumb-turn it may be released therefrom by a duplicate guest key as well as by the emergency key, and when the latch is dead-locked by either the guest key or the emergency key, it may be released therefrom by the thumb-turn, and finally when the latch is dead-locked by the emergency key it can only be released therefrom from the outside 100 by the emergency key, but it can also be released therefrom from the inside by the thumb-turn.

While I have herein described a particular embodiment of my invention, it is to be understood that the same may be varied in detail and arrangement of parts without departing from the spirit and scope of my invention.

What I claim is:

1. In a lock, a latch bolt, means for retracting said latch bolt by a series of keys including a guest key and an emergency key, means for dead-locking said latch bolt operable by said guest and emergency keys to prevent retraction of said latch bolt by any except said guest or emergency key, and means to prevent retraction of the latch bolt by said guest key when dead-locked by the 115 operation of said emergency key.

2. In a lock, a latch bolt, means for re-
tracting said latch bolt by the operation of
any of a series of keys including a guest key
and an emergency key, dead-locking means
5 for said latch bolt operable by said guest
and emergency keys respectively to prevent
retraction of said latch bolt by any except
said guest or emergency key, a roll-back ar-
ranged to operate said dead-locking means
10 from the inner side of the door, means to
permit operation of said dead-locking means
interchangeably by said guest key and said
roll-back and to prevent release of said
dead-locking means by said guest key when
15 the latter is thrown into operation by opera-
tion of said emergency key.
3. In a lock, a latch bolt, means for re-
tracting said latch bolt by the operation of
any of a series of keys including a guest key
20 and an emergency key, means operable by
said guest key and said emergency key for
dead-locking said latch bolt against retrac-
tion by the operation of any of said keys
except said guest and emergency keys re-
25 spectively, a roll-back operable from the in-
ner side of the door to throw said dead-
locking means into and out of action, and
means constructed and arranged to permit
the release of said dead-locking means by
30 said guest key and said roll-back inter-
changeably when thrown into action by
either said guest key or said roll-back, and
means to prevent release of said dead-lock-
ing means by said guest key when thrown
35 into action by said emergency key and to
permit release of said dead-locking means
by said roll-back when thrown into action
by said emergency key.
4. In a lock, a latch bolt, means for re-
40 tracting said latch bolt by the operation of
any of a series of keys including a guest key
and an emergency key, dead-locking means
for said latch bolt operable by said guest
and emergency keys respectively to
45 throw said latch retracting means out of
range of operation by the other keys of said
series, means to permit release of said dead-
locking means by the operation of said guest
and emergency keys respectively when
50 thrown into action by said guest key, and
means to prevent release of said dead-lock-
ing means by the operation of said guest
key when thrown into action by said emer-
gency key.
5. In a lock, a latch bolt, means operable
55 by any of a series of keys including a guest
key and an emergency key for retracting
said latch bolt, means operable by said guest
key and said emergency key for throwing
60 said latch retracting mechanism out of range
of retraction by all of said keys, a roll-back
operable from the inner side of the door for
actuating said dead-locking means, means
for permitting the release of said dead-lock-
65 ing means by said guest key and said roll-
back interchangeably when thrown into ac-
tion by either of said members respectively
and to prevent release of said dead-locking
means by said guest key when thrown into
70 action by the operation of said emergency
key but to permit release of said dead-lock-
ing means by said roll-back when thrown
into action by said emergency key.
6. In a lock, a latch bolt, a dead-locking
slide, means for retracting said latch bolt
carried by said slide and operable by any
75 of a series of keys including a guest and
an emergency key when said slide is in in-
operative position, means for moving said
slide to carry said bolt retracting mecha-
nism out of range of operation of all of said
80 keys when said slide is thrown into action
by either said guest or emergency key, a roll-
back operable from the inner side of the
door for actuating said slide into and out of
action, means arranged to permit release of
85 said dead-locking slide interchangeably by
said guest key and said roll-back when
thrown into action by either of said mem-
bers, and means to prevent release of said
slide by the operation of said guest key when
90 thrown into action by said emergency key,
said latter means arranged to permit re-
lease of said dead-locking slide by said roll-
back when said slide is thrown into action
by said emergency key.
7. In a lock, a latch bolt, a dead-locking
member therefor, bolt actuating mechanism
carried by said member operable by any of
100 a series of keys including a guest key and
an emergency key, means operable by said
guest key and said emergency key respec-
tively to actuate said member to carry said
latch retracting means out of range of oper-
ation of the keys of the series, a roll-back
105 operable from the inner side of the door
also to actuate said member to carry said
latch retracting means out of range of oper-
ation of the keys of the series, a guard
tumbler constructed and arranged to per-
110 mit actuation of said dead-locking member
to and from operative position by said guest
key and roll-back interchangeably and to
prevent release of said member by opera-
tion of said guest key when thrown into ac-
tion by said emergency key, said guard
tumbler arranged to permit release of said
115 dead-locking member by said roll-back when
thrown into action by said emergency key.
8. In a lock, a latch bolt, a dead-locking
slide, bolt-actuating mechanism carried by
120 said slide and operable by any of a series of
keys including a guest key and an emer-
gency key, means operable by said guest key
to move said slide to and from operative
position, means operable by said emergency
key for moving said slide to and from opera-
tive position, a roll-back operable from the
inner side of the door for moving said slide
125 to and from operative position, a guard
130

- tumbler operable by the operation of said guest key and said roll-back during the operation of said slide, and means on said slide coöperating with said guard tumbler constructed and arranged to permit release of said slide by said guest key and said roll-back interchangeably unless thrown into action by either of said members and to prevent release of said slide by the operation of 5 said guest key when thrown into action by said emergency key, said guard tumbler being arranged to permit the release of said slide by said roll-back when thrown into action by said emergency key.
- 10 9. In a lock, a latch-bolt, a dead-locking slide therefor, means for retracting said latch-bolt carried by said slide, a key-controlled member for actuating said bolt-retracting means operable by any of a series 20 of keys including a guest key and an emergency key, a key-controlled member for moving said dead-locking slide into and out of operative position operable by said emergency key and said guest key respectively, 25 a guard member for preventing release of said slide by said guest key when said slide is thrown to operative position by said emergency key, a roll-back operable from the inner side of the door to move said slide into 30 and out of operative position, said guard member constructed and arranged to be operated by said roll-back and said guest key controlled member to permit release of said slide by operation of said roll-back and said 35 guest key interchangeably.
10. In a lock, a latch-bolt, a dead-locking member therefor, bolt-retracting means carried by said dead-locking member, a key-controlled member operable by any of a series 40 of keys for actuating said bolt-retracting means, a key-controlled member operable by said emergency key and said guest key to actuate said dead-locking member to carry said bolt-retracting means out of range 45 of said first key-controlled member, a key-controlled member operable by said guest key and a member coöperating therewith to prevent return of said dead-locking means to 50 inoperative position by said guest key when thrown into action by said emergency key but to permit such return by said roll-back when said dead-locking member is moved to operative position by said emergency key.
- 55 11. In a lock, a latch-bolt, a dead-locking slide, latch-bolt retracting means carried by said slide, a key-controlled member operable by any of a series of keys, including a guest key and an emergency key, to actuate said bolt-retracting means, a key-controlled member operable by said emergency key and guest key respectively to actuate said dead-locking slide to carry said bolt-retracting means out of range of said first key-controlled member, a guard-tumbler adjacent 60
- said dead-locking slide operable by said emergency and guest key controlled members respectively, coöperating means on said slide and said tumbler respectively, constructed and arranged to prevent release of 70 said dead-locking slide by said guest key controlled member when said slide is thrown to operative position by said emergency key controlled member.
12. In a lock, a latch-bolt, a dead-locking member therefor, latch-retracting means carried by said member, a key-controlled member operable by any of a series of keys, including a guest key and an emergency key, to actuate said bolt-retracting means 75 when in normal position, a key-controlled member operable by said emergency key and guest key respectively, to actuate said dead-locking member to move said latch-retracting means out of range of said first 80 key-controlled member, a roll-back operable from the inner side of the door likewise to actuate said dead-locking member, a guard-tumbler adjacent said dead-locking member arranged to be actuated by said guest key-controlled member and by said roll-back to permit actuation of said dead-locking member to and from operative position by operation of said guest key and said roll-back interchangeably, and arranged to prevent return of said dead-locking member to normal position by operation of said guest key when thrown into action by said emergency key-controlled member, said tumbler having means controlled by said roll-back 90 to permit said dead-locking slide to be moved into inoperative position by said roll-back when thrown into operative position by said emergency key-controlled member.
13. In a lock, a latch-bolt, a dead-locking member therefor, latch-retracting means carried by said member, a key-controlled cam arm operable by a series of keys, including a guest key and an emergency key to actuate said bolt-retracting means when in normal position, a key-controlled cam arm in line with said first arm and operable by said emergency key and said guest key to actuate said dead-locking slide to carry said latch-retracting means out of and into range of 105 said first key-controlled cam arm, a guard-tumbler pivoted adjacent said dead-locking member, a third key-controlled cam arm operable by said guest key, operating means on said guard tumbler and said dead-locking member to hold said tumbler in the path of said third key-controlled arm when said dead-locking member is actuated by said emergency key-controlled member to prevent release of said dead-locking member by 110 said guest key but to permit return of said dead-locking member by said emergency key.
14. In a lock, a latch-bolt, a dead-locking member therefor, bolt-retracting means carried by 115
- 120
- 125
- 130

- ried by said member, a key-controlled cam arm operable by any of a series of keys to actuate said bolt-retracting means when in normal position, a key-controlled cam arm 5 operable by said emergency key and said guest key respectively to actuate said dead-locking member to carry said bolt-retracting means out of and into range of said first key-controlled member, a guard tumbler adjacent said dead-locking member, a key-controlled cam arm operable in conjunction with said emergency key-controlled cam arm by said guest key, coöperating means on said dead-locking member and 10 said guard-tumbler respectively, arranged to hold said guard-tumbler in the path of said last key-controlled member when said dead-locking member is actuated by said emergency key to prevent release of said member 15 by said guest key, a roll-back operable from the inner side of the lock to actuate said dead-locking member into and out of operative position, means on said guard-tumbler coöperating with said roll-back to position 20 said coöperating means between said tumbler and said dead-locking member to permit of actuation of said dead-locking member into and out of operative position by 25 operation of said guest key and said roll-back interchangeably.
15. In a lock, a latch-bolt, a dead-locking device therefor, latch-retracting means carried by said dead-locking device, a key-controlled member operable by any of a series 30 of keys, including a guest key and an emergency key for actuating said latch-retracting mechanism from the outer side of the lock when said dead-locking device is out of action, said latch-retracting means being 35 out of range of operation of said externally controlled means when said dead-locking device is in action, and means controlled by said guest key and said emergency key for moving said dead-locking means to operative 40 position.
16. In a lock, a latch-bolt, a dead-locking slide, means at the inner side of the lock for throwing said slide into or out of action, separate means carried by said dead-locking slide arranged to retract said latch-bolt, a key-controlled member operable by any of 45 a series of keys, including a guest key and an emergency key, coöperating with said
- latch-retracting means independently of said means for throwing the slide into and out of action, and operable from the outer side of the door only, and coöperating with said latch-retracting means only when the dead-locking slide is thrown off and out of action, means operable by said emergency 50 key and said guest key respectively for throwing said dead-locking slide into action from the outer side of the door, and means for preventing the release of said dead-locking slide by said guest key when thrown into 55 action by said emergency key.
17. In a lock, a latch-bolt, a roll-back therefor operable from the inner side of the door only, a dead-locking slide, latch-bolt retracting means carried by said slide, a key-controlled member operable by said guest key and said emergency key respectively to move said dead-locking slide to carry said bolt-retracting means out of range of said first key-controlled member, a guard-tumbler 60 coöperating with said dead-locking slide, and means operable only by said guest key and coöperating with said guard-tumbler to prevent release of said dead-locking means by operation of said guest key when 65 dead-locked by said emergency key.
18. In a lock, a latch-bolt, a roll-back therefor operable from the inner side of the door only, a dead-locking slide, bolt-retracting means carried by said slide, a key-controlled member operable by any of a series 70 of keys, including a guest key and an emergency key to actuate said dead-locking slide to carry said bolt-actuating means out of range of said first key-controlled member, a second roll-back operable from the inner side of the door to actuate said dead-locking slide into and out of operative position, a guard-tumbler coöperating with said dead-locking slide and constructed and arranged 75 to permit actuation of said dead-locking slide into and out of operative position by said guest key and said second roll-back interchangeably, and to prevent release of 80 said dead-locking means by operation of said guest key when thrown into action by said emergency key.

HENRY G. VOIGHT.
